UNITED STATES PATENT OFFICE.

EDWARD LINDMUELLER, OF CLEVELAND, OHIO, ASSIGNOR OF THREE-FOURTHS TO
JOSEPH C. McCLURE, OF CLEVELAND, OHIO.

OIL-ATOMIZER.

1,088,711.

Specification of Letters Patent.

Patented Mar. 3, 1914.

Application filed February 27, 1913. Serial No. 751,111.

To all whom it may concern:

Be it known that I, EDWARD LINDMUELLER, a citizen of the United States, residing at Cleveland, in the county of Cuyahoga and State of Ohio, have invented certain new and useful Improvements in Oil-Atomizers, of which the following is a specification.

My present invention relates to improvements in oil atomizers and is designed particularly for use in connection with that class of lubricators wherein the atomized oil, as a lubricant, is carried by fluid pressure to the part to be lubricated.

The object of the invention is the provision of a device for lubricating a piston within a cylinder, operating under steam or other motive fluid pressure, in an economical, facile and efficient manner, and this object is accomplished by the utilization of the novel form of atomizer as will be herein-after pointed out.

In the accompanying drawings I have illustrated one complete example of the physical embodiment of my invention constructed according to the best mode I have so far devised for the practical application of the principles of my invention.

Figure 1 is a view showing a portion of a main steam line or pipe from a boiler to a cylinder, with my improved oil atomizer attached thereto and shown in vertical section. Fig. 2 is a transverse section on line 2—2 Fig. 1. Fig. 3 is a vertical sectional view on line 3—3 of Fig. 1.

In order to secure the highest efficiency and uniform distribution of the oil as a lubricant in the cylinder in which a steam piston is moving it is desirable that the lubricant be carried to the cylinder in an atomized condition rather than in drops, and to accomplish this condition I provide an atomizer by which the oil is separated into fine particles, and the particles are carried by the steam to the steam cylinder, through the main steam line or pipe 1.

The atomizer comprises a metallic casing or casting 2 of suitable dimensions and shape. In the drawings I have illustrated the shell or casing 2 of cylindrical form, but it will of course be understood that other desirable forms may be adopted to suit varying conditions. The cylindrical shell is provided with an inlet perforation for the oil feed pipe 3, and an outlet perforation for the pipe 4.

Within the shell are arranged a suitable number of shelves or plates 5, the upper one being located just below the oil inlet, and the lowermost one located just above the outlet pipe. The shelves are arranged in staggered relation and extend transversely across the cylinder or shell covering the whole area except for an opening 6 against the wall of the cylinder.

The shelves are slightly inclined downwardly, and their upper surfaces are convexed, (as seen best in Fig. 3), so that oil may freely run over the upper surface. The openings 6, it will be seen in Fig. 1, are arranged so that the successive openings are located at opposite points in the cylinder. This arrangement of shelves and their convex formation together with their downward incline, cause the oil, flowing into the cylinder or shell through pipe 3, to flow over the shelves in sheets, taking zigzag courses, and the filmy condition of the oil renders its atomization comparatively simple.

To atomize the oil I convey steam to the shell through the branch pipe 7 connected to the steam pipe 1 above the atomizer, and the steam enters at the top of the atomizer through a perforation. The passage of the steam through the atomizer shell, in close intercourse with the filmy oil, breaks the oil into fine particles, and the atomized oil, together with the steam as a vehicle, is carried out through the outlet pipe 4 into the steam pipe, and thence to the place to be lubricated. In this manner I perfect a great saving in the consumption of oil or lubricant compared with the old way of using a sight lubricator and feeding the oil to the engine in drops, which is uncertain in its results.

My invention causes a complete atomization of the oil as it passes through the atomizer, with the result that the commingling of this vapor oil with the steam causes an equal distribution of the lubricant into all parts of the engine cylinder.

The following subject matter is disclaimed herein:

As a new article of manufacture, in an oil vaporizing device, a closed vessel provided with an inlet opening for steam, an inlet for oil and an outlet for vaporized oil and steam, said vessel including a part in its interior integral with its walls having a downwardly slanting upper surface, said

vessel including a passage through which its upper and lower parts communicate with one another and the inlets and outlets communicate with one another.

5. What I claim as my invention is:

1. The combination with a steam pipe and branches therefrom, of a shell having an inlet, a series of shelves each closing the cross area of the shell and downwardly inclined toward an opening located diametrically opposite an opening in each adjoining shelf, and the upper surface of each shelf being convex in formation.
- 10
- 15

2. An oil atomizer including a shell having a series of shelves with convex upper surfaces, and each shelf closing the cross area of the shell and downwardly inclined toward an opening located diametrically opposite the opening in an adjoining shelf.

In testimony whereof I affix my signature 20
in presence of two witnesses.

EDWARD LINDMUELLER.
